ALTERNATE FEED SWITCH FOR FIREARMS

Edward W. Hopkins, Longmeadow, Mass., assignor to the United States of America as represented by the Secretary of War

Application October 13, 1949, Serial No. 121,084
2 Claims. (Cl. 89—33)

(Granted under the act of March 3, 1883, as amended April 30, 1928; 370 O. G. 757)

1

The invention described herein may be manufactured by or for the Government for governmental purposes without the payment of any royalty thereon.

This invention relates to a reversible feed mechanism for machine guns and is directed more particularly to simplified means for alternating the direction from which cartridges are fed into a gun of the well-known Browning type.

The detailed feeding mechanism of such guns is fully described in U. S. Patent No. 1,803,351 held by Frederick L. Moore and consequently need not be here repeated in detail. However, in order to adequately explain the present invention, it should be pointed out that the Browning type of feeding mechanism includes a feed slide which is actuated by an elongated pivotal lever to successively advance the cartridges of a linked belt into position for extraction therefrom upon recoil of the bolt. A pair of intersecting cam grooves are formed along the top of the bolt for selectively engaging the rear end of the pivotal lever. As the bolt recoils and counter-recoils, the lever is oscillated in accordance with the contour of the engaged cam groove and thereby effects transverse reciprocation of the slide. Since these cam grooves intersect, the continuous outlines thereof are interrupted by one another at the point of intersection. Accordingly, there is provided a rotary type bolt switch having a cam track therein for completing one or the other of the cam grooves to provide a continuous path for the rear end of the belt feed lever. The direction from which the cartridges are advanced into the feedway of the gun is therefore dependent upon the particular cam groove in which the feed lever is engaged. Since the aforesaid switch must necessarily be flush with the top surface of the bolt, a suitable circular recess is provided therein at the point of intersection of the cam grooves. Obviously, the removal of sufficient metal from the bolt to form the desired bolt switch recess detracts from the optimum endurance life of such a highly stressed member.

It is therefore an object of this invention to provide a simplified means for alternating the feed of a Browning type machine gun wherein the present rotary switch and bolt recess therefor may be eliminated.

The specific nature of the invention as well as other objects and advantages thereof will clearly appear from a description of a preferred embodiment as shown in the accompanying drawings in which:

2

Fig. 1 is a top view of an alternate feed bolt with the switch inserts of this invention positioned for left hand feed.

Fig. 2 is a fragmentary enlarged view of Fig. 1 showing the switch inserts positioned for right hand feed.

Fig. 3 is a cross-sectional view taken along the line 3—3 in Fig. 2.

Fig. 4 is a cross-sectional view taken through 10 the feedway of a Browning type machine gun and showing the feeding mechanism arranged for left hand feed.

Fig. 5 is a cross-sectional view similar to Fig. 4 but showing the arrangement for right hand feed.

Fig. 6 is a perspective view of the roll pin used to secure the switch insert in the bolt.

Fig. 7 is a top view of a Browning type machine gun with the cover removed and showing the feeding mechanism arranged for left hand feed.

Fig. 8 is a perspective view of the switch insert of this invention.

Referring now to the drawings, especially Figs. 4, 5 and 7, there is illustrated a cartridge belt 25 feed mechanism as applied to a machine gun of the Browning type, although it will be understood that the principles of the invention are applicable with equal facility to any automatic weapon which is similarly fed.

As in the case of all machine guns of the Browning type, a breech bolt 10 having a cartridge extractor 28 pivoted thereto is mounted in a receiver 11 for reciprocable movement from and to a battery position.

The cartridge belt feed mechanism comprises generally a slide 12, a belt feeding pawl 13, a belt holding pawl 14, and a belt feed lever 15. Slide 12 is arranged to reciprocate transversely of bolt 10 and feed cartridges 16 of a linked belt

40 17 through the medium of pawl 13 in the manner well known in the art. Belt feed lever 15 is pivoted intermediate of its ends to the underside of the gun cover (not shown) and is engaged at its front end with slide 12 and at its rear end with bolt 10. Thus as bolt 10 recoils, lever 15 is pivoted to actuate slide 12 so as to engage the foremost cartridge 16 of belt 17 and then as bolt 10 counter-recoils, lever 15 actuates slide 12 to move such cartridge along the feedway 29 of receiver 11 into position to be pulled out of belt 17 by extractor 28 when the previously extracted cartridge is fired.

A pair of intersecting cam grooves 18 and 19 are formed along the top of bolt 10 and extend 55 from the front face thereof to terminate slightly

forward of its rear end. Grooves 18 and 19 intersect substantially midway along bolt 10 and thereby serve to interrupt the continuous outline of one another at such point of intersection. Consequently, there is provided a pair of identical switch inserts 20 to selectively complete the interrupted portion of cam grooves 18 and 19 in the manner illustrated in Figs. 1 and 2.

Switch inserts 20 are preferably unitary members having a trapezoidal head portion 21 and a pin-shaped body 22 extending therefrom. Vertical holes 23 are provided in cam grooves 18 and 19 and such holes extend sufficiently into the body of bolt 10 to fully receive the pin-shaped body 22 of insert 20, the head portion 21 thereof being thereby arranged to lie flush with the top of bolt 10. The distance between the parallel sides of head portion 21 is such that inserts 20 engage snugly in cam grooves 18 and 19 when assembled to bolt 10. The non-parallel sides 24 of head portions 21 are convergingly sloped at such angle that when inserts 20 lie in cam groove 18 or 19 on either side of the interrupted portion thereof, one sloping side of each head portion 21 is aligned with the interrupted wall of the intersecting cam groove. Thus, as shown in Fig. 1, switch inserts 20 complete cam groove 18 while blocking off the interrupted portions of cam groove 19. The converse is true in the case of the position shown in Fig. 2.

As illustrated particularly well in Fig. 2 and Fig. 3, holes 23 are each partially intersected by a second hole 25 drilled transversely through bolt 10. The latter holes 25 each receive a split roll pin 26 arranged to engage in a circumferential groove 27 provided adjacent the free end of pin-shaped body 22 of switch insert 20. Since roll pins 26 are of slightly larger diameter than holes 25, inserts 20 are thereby securely keyed in bolt 10 against loosening from the shock and vibration of continuous firing.

When inserts 20 are assembled to bolt 10 in the position indicated in Fig. 1, the gun is adapted to be fed from the left hand side (see Fig. 4). As bolt 10 recoils, lever 15 is pivoted so as to actuate slide 12 outwardly to the left and cause belt feeding pawl 13 to engage the foremost of the linked cartridges 16. Then as bolt 10 counter-recoils, lever 15 is pivoted to actuate slide 15 inwardly to the right and thereby bring the cartridge 16 engaged by belt feeding pawl 13 into position to be engaged by extractor 28.

In the event it is desired to feed from the right hand side of the gun, switch inserts 20 are removed from cam groove 18 and replaced in cam

groove 19 in the manner of Fig. 2. At the same time, slide 12, pawls 13 and 14 are reversed as is customary in the Browning type machine gun. The fulcrum point (not shown) of lever 15 is also changed to accommodate the reversed pivoting movement thereof and consequently the feed mechanism is thereby arranged for the right hand feed of Fig. 5.

It can thus be readily seen that the substitution of switch inserts 20 for the previous type of rotary bolt switch entirely eliminates the necessity for providing a recess in the top of the bolt, a factor which is highly important in increasing the endurance life of such a highly stressed component. Moreover, the simplicity of manufacturing inserts 20 in comparison to the more complicated fabrication of the previous rotary type bolt switch introduces a significant decrease in the cost of manufacture which is always of the utmost importance in mass production.

I claim:

1. In a machine gun, a bolt having a pair of intersecting cam grooves formed along the top thereof, both of said cam grooves having interrupted side walls only at the point of intersection with one another, and a pair of symmetrical members fixedly secured to said bolt, said inserts being provided with a trapezoidal head portion and a pin shaped body portion, said head portion having a vertical thickness equivalent to the depth of said cam grooves whereby the top of said insert lies flush with the top of said bolt, one of the non-parallel sides of each head portion arranged to be in alignment with the side wall of that particular cam groove which intersects the cam groove in which said inserts are secured whereby a continuous path is defined in said cam groove, said pin shaped body portion arranged to extend vertically into said bolt.
2. The combination of claim 1 plus means for cooperating with said pin shaped body portion to securely key said inserts in said bolt.

EDWARD W. HOPKINS.
